UNITED STATES PATENT OFFICE.

VALDEMAR RASMUSSEN, OF OMAHA, NEBRASKA.

COMBINATION-SPIKE.

No. 806,186.

Specification of Letters Patent.

Patented Dec. 5, 1905.

Application filed September 6, 1904. Serial No. 223,435.

To all whom it may concern:

Be it known that I, VALDEMAR RASMUSSEN, a citizen of the United States, residing at Omaha, in the county of Douglas and State 5 of Nebraska, have invented a new and useful Combination-Spike, of which the following is a specification.

The object of my invention is to produce a spike which has all the advantages of the 10 hitherto-used spikes, but besides has the superiority over the old ones in that my combination-spike will stay in its place against any shrinkage, shaking, or any other disturbance, but at the same time is easy to remove when desired. I attain these objects 15 by the mechanism illustrated in the accompanying drawings, in which—

Figure 1 shows my combination - spike driven into a railroad-tie for fastening a rail 20 to the same; Fig. 2, a side view of the combination-spike before used as fastener; Fig. 3, a front view of Fig. 2, and Fig. 4 a side view of a combination-spike when in use as fastener.

Similar numerals refer to similar parts 25 throughout the several views.

My combination-spike is composed of two pieces—the main piece or the genuine spike 1, which has to be driven in, (here in the tie,) and its key, the holder 2. The main piece 30 1 is pointed at its lower end and shaped as shown on the drawings, Figs. 2 and 3, to give room for the hook 3, which forms the lower end of 2 and the holder itself. Further, the main piece 1 is provided with a kind of a shoulder 4, which matches a cut or recess 5 in the key 2. The main piece is provided with 35 a head 6, shaped according to the purpose the

spike is intended for, here the shape of a rail-spike, and the key 2 is provided with a similar head.

When they are to be used, the main spike and its key are placed in the position shown in Fig. 2. The spike is then forced into the tie by striking the head of the main spike with a hammer until the head of the key rests 40 upon the rail-flange. Any further striking upon the main spike will then force the hook 3 of the key into the wood, because of engagement of the shoulder 4 with the inclined 45 side of the recess 5 in the key. The hook 3 thus prevents the spike from working out of 50 the tie. When it is desired to remove the spike, it is only necessary to withdraw the main spike until the shoulder 4 engages with the recess 5. The spike may then be easily 55 removed.

Having so described my invention, what I claim, and desire to secure by Letters Patent, is—

The combination with a main spike having 60 at its lower end a lateral projection provided with a recess in its upper side and also having on the same side a cam projection between its ends, of a key having at its lower end a hook shaped to engage the recess of 65 the main spike and having between its ends a recess adapted to be engaged by the cam projection of the main spike, substantially as described.

VALDEMAR RASMUSSEN.
